(57) **CLAIM**

The ornamental design for a seat belt holding clip, as shown and described.

DESCRIPTION

FIG. 1 is a perspective view of a seat belt holding clip showing my new design;

FIG. 2 is a side view (opposite side view is mirror image) thereof;

FIG. 3 is a front view thereof;

FIG. 4 is a back view thereof;

FIG. 5 is a top view thereof; and,

FIG. 6 is a bottom view thereof.

The broken lines in FIGS. 1 and 3 indicate that the nubs are not part of the claimed design. The broken lines in FIGS. 2 and 6 indicate that the nubs and the platform on which they rest are not part of the claimed design.
